CLAIM

The ornamental design for a load carrying handle, as shown and described.

DESCRIPTION

FIG. 1 is a perspective view of the load carrying handle showing my new design;

FIG. 2 is a top plan view thereof, the bottom plan view being a mirror image thereof;

FIG. 3 is a rear elevational view thereof;

FIG. 4 is a side elevational view taken from the right side thereof;

FIG. 5 is a side elevational view taken from the left side thereof; and,

FIG. 6 is a front elevational view thereof.
